BABY CRIB ACCESSORY RACK

Joy M. Osborn, 131 K St. SW., Quincy, Wash. 98848

Filed May 15, 1970, Ser. No. 23,017

Term of patent 14 years

Int. Cl. D6—99.

U.S. Cl. D33—3

FIG. 1

FIG. 3

FIG. 1 is a left front perspective view of the baby crib accessory rack embodying my new design with the tray in an open position;

FIG. 2 is a right rear perspective view as viewed from the bottom; and

FIG. 3 is a left rear perspective view with the tray in a collapsed position.

I claim:

The ornamental design for a baby crib accessory rack, substantially as shown.
